R. A. WILSON,
WELL CASING SPEAR,
APPLICATION FILED AUG. 2, 1920.

1,418,766.

Patented June 6, 1922.

UNITED STATES PATENT OFFICE.

ROBERT A. WILSON, OF DALLAS, TEXAS, ASSIGNOR TO THE GUIBERSON CORPORATION, OF DALLAS, TEXAS, A CORPORATION OF DELAWARE.

WELL-CASING SPEAR.

1,418,766.

Specification of Letters Patent. Patented June 6, 1922.

Application filed August 2, 1920. Serial No. 400,584.

To all whom it may concern:

Be it known that I, ROBERT A. WILSON, a citizen of the United States, residing at Dallas, in the county of Dallas and State of 5 Texas, have invented certain new and useful Improvements in Well-Casing Spears, of which the following is a specification.

This invention has to do with well casing spears.

10 The purpose of the invention is to provide a spear that can be engaged at any desired point in the casing, or released at will and then raised or lowered in the well, without the use of trip devices or the necessity of 15 first bringing it to the surface. A further result sought is to produce a spear of a substantial and simple nature in which a head, which may have water courses, may be employed and the use of catches, release pins 20 and tripping devices, obviated. Another feature is the reduction of the number of parts usually employed.

In carrying out the invention I provide a mandrel having a spear head at its lower 25 end, said head having a larger diameter than the mandrel. A spring sustained weight is mounted on the mandrel. The lower end of the weight is pivotally connected with casing engaging slips, slidably

30 confined on the head and normally within the diameter of the spear head. By imparting a quick upward movement to the mandrel the slips are forced outward into engagement with the casing owing to the inertia of the weight. The spear is released 35 and the slips withdrawn, by forcing the mandrel downward. Other features of the invention will be hereinafter pointed out.

The invention will be more readily understood from a reading of the following 40 specification and by reference to the accompanying drawings, in which an example of the invention is shown, and wherein:

Fig. 1 is a view in elevation of a device 45 constructed in accordance with my invention,

Fig. 2 is an enlarged view of the device, the weight being shown partly in section,

Fig. 3 is a cross-sectional detail on the line 50 3-3 of Fig. 2,

Fig. 4 is a cross-sectional detail on the line 4-4 of Fig. 2, and

Fig. 5 is a cross-sectional detail on the line 5-5 of Fig. 2.

In the drawings the numeral 10 designates 55 a cylindrical mandrel which has a rounded spear head 11 at its lower end, the head being larger in diameter than the mandrel. At its upper end the mandrel has a tapered screw-threaded stub 12 by which the mandrel may be joined to the support by which it is lowered into the well. Just below the stub the mandrel is provided with an angular wrench grip 13 so that it may be engaged by a suitable tool for screwing the 60 stub 12 into the support.

A collar 14 surrounds the mandrel a short distance from the head and is fastened in position. This collar supports a coiled spring 15 which surrounds the mandrel. A 70 weight in the form of a sleeve 16 is disposed on the mandrel and has a counter-bore 17 receiving the spring which latter supports the sleeve at its upper end. At its lower end the sleeve has depending ears 18 and between each pair of ears the upper end of a link 19 is pivoted. I have shown three of these links equally spaced around the mandrel and below the collar 14, however, the invention is not to be limited to this number. Each link has its lower end pivoted in a pair of ears 20 provided on the upper 75 ends of slips 21.

Each slip 21 has its outer face provided with arcuate teeth disposed circumferentially of said spear and formed so as to engage in a surface when the spear is elevated as is usual in casing spears. The inner faces 22 of the slips are inclined inwardly and upwardly so as to conform to 80 inclined guideways 23 formed on the upper portion of the head 11. It will be noted that the guideways 23 begin substantially at the point of greatest diameter of the head 11, and extend to the upper end of the head which is gradually reduced in diameter. Each guideway has at its center a radial rib 85 24 which has its lower end rounded and merged into the surface of the head 11, so as to confine it within the diameter of the head. 90

It is preferable to give the ribs 24 a dovetail shape in cross section and to provide the slips with correspondingly shaped grooves 95 25 receiving said ribs, whereby the slips are held against radial displacement, but are free to slide up and down the guideways. However, the invention is not to be limited to this manner of confining the slips and any 100 105

other suitable expedient or means for accomplishing the results, may be resorted to. It will be noted that the teeth on the outer surface of the slips have their edges in substantially the same vertical plane so that they may easily engage with the inner surface of the well casing. It will be plain that by effecting a relative movement between the slips and the head, said slips will be extended radially by reason of the inclined guideways 23, whereas a reverse movement will retract the slips.

When the spear is lowered into the well the slips will be in their normal position which is at the upper ends of the guideways 23, and in this position they will be well within the mean diameter on the head 11. They are supported in this position by means of the spring 15 which holds the weight sleeve 16 in an elevated position. It will be seen that the spear may be lowered to the desired point in the well without catching on the side of the casing. When it is desired to engage the spear with the casing it is simply necessary to impart a sudden upward movement to the mandrel 10. This results in the slips 21 being forced outwardly so that their teeth engage in the wall of the casing. This is due to the fact that the inertia of the weight 16 tends to keep it in a state of rest. Thus when the said upward movement is imparted, the spring 15 will be compressed and the head 11 will move upwardly. When the head 11 moves upwardly the inclined guideways 23 riding up the faces 22 of the slips, will force said slips outwardly until their teeth bite into the casing. The spring, of course, must be of such a tension as to support the slips but not resist the inertia of the weight 16.

When it is desired to release the slips from engagement with the casing it is merely necessary to force the mandrel 10 downwardly so that the guideways 23 are moved down the faces 22 whereby the slips are withdrawn. When this is done the compression spring 15 will be freed and will tend to elevate the weight 16 whereby the slips will be carried to their normal position. From the foregoing it will be apparent that the spear may be engaged with the casing at any point desired and may be released therefrom at will; and further after being released said spear may be raised or lowered in the well to any point and then re-engaged with the casing if desired, all of which is accomplished without bringing the spear to the surface to be adjusted or set. It is pointed out that the action of the slips is positive and each has a positive bearing on the head 11. The parts are of such a nature that they may be strongly constructed and will undergo heavy duty without giving trouble, thus increasing the life of the spear and making repairs not only infrequent, but easy.

While I have shown a compression spring it is to be understood that any other kind of spring could be used and the invention is not to be limited to any particular kind of spring. Various structures could be evolved for resiliently sustaining the weight and the invention includes all such modifications as come within the scope of the appended claims.

What I claim, is:

1. In a well casing spear, a mandrel, a head carried by the mandrel, radially displaceable slips mounted on the head, and a resiliently sustained weight mounted on the mandrel and having connection with the slips.

2. In a well casing spear, a mandrel, a head carried by the mandrel, said head having inclined portions, slips mounted on said inclined portions of the head, and a resiliently sustained weight mounted on the mandrel and connected with the slips, the head and weight being adapted to undergo relative movement whereby the slips move radially.

3. In a well casing spear, a mandrel, a head fixed on the lower end of the mandrel, said head having inclined guideways, slips confined to a vertical movement on the guideways, and means for checking a relative upward movement of the slips when the mandrel and head are suddenly moved upwardly.

4. In a well casing spear, a mandrel, a head carried at the lower end of the mandrel and provided with inclined guideways, slips slideable on said guideways, a spring supported weight member surrounding the mandrel, and pivoted connections between the weight member and the slips.

5. In a well casing spear, a mandrel, a head at the lower end of the mandrel, radially displaceable slips mounted on the head, a coiled spring supported on the mandrel above the head, a weight sleeve supported on the spring and surrounding the mandrel, and pivoted links connecting the sleeve with the slips.

6. In a well casing spear, a mandrel, an enlarged head fixed at the lower end of the mandrel, said head having inclined guideways, retaining ribs extending longitudinally of said guideways, slips slidably confined on the guideways and receiving said ribs, a collar mounted on the mandrel above the head, a coiled spring supported on the collar and surrounding the mandrel, a weight sleeve surrounding the spring and having its upper end supported thereby, and links pivotally connecting the lower end of the sleeve with the upper ends of the slips, whereby said slips are supported.

7. In a well casing spear, a plurality of gripping slips, a support having inclined faces on which the slips are mounted to slide,

a weight member, a coiled spring on which the member is sustained, and connections between the slips and the weight member pivoted thereto.

5 8. In a well casing spear, a plurality of gripping slips, a support having inclined faces on which the slips are mounted to slide,

a weight sleeve, a coiled spring telescoping into the sleeve and supporting the same, and pivoted connections between the sleeve 10 and the slips sustaining the latter.

In testimony whereof I affix my signature.

ROBERT A. WILSON.
